[57] CLAIM

The ornamental design for a portable beverage holder, as shown and described.

DESCRIPTION

FIG. 1 is a left side elevational view of a portable beverage holder showing my new design in use;

FIG. 2 is a front elevational view;

FIG. 3 is a right side elevational view;

FIG. 4 is a top plan view;

FIG. 5 is a bottom plan view;

FIG. 6 is a rear elevational view; and,

FIG. 7 is a left side elevational view.

The broken line showing of a bicycle in FIG. 1 is for illustrative purposes only and forms no part of the claimed design.

FIG. 1

FIG. 2

FIG. 3

FIG. 4

FIG. 5

FIG. 6

FIG. 7
